Gray & Smith
ATTORNEYS.

UNITED STATES PATENT OFFICE

2,454,944

GARMENT HANGER

Harry E. Reynolds, Detroit, Mich.

Application May 2, 1945, Serial No. 591,444

7 Claims. (Cl. 223—85)

1

This invention relates to garment hangers and more particularly to a hanger which is especially useful for hanging hose or stockings to be dried. The invention, however, is not to be considered as restricted to such use as it will be evident that various types of garments or apparel other than hose may be suspended from a hanger embodying the present invention.

An object of the invention is to provide a hanger for hose or other articles of apparel having improved devices for releasably gripping the articles, such devices being preferably formed of wire and being supported in improved manner such as to maintain the devices at all times in proper position for ready use.

Another object of the invention is to provide an improved wire formed garment hanger having any suitable number of hose clips supported on the hanger frame in improved manner.

A further object of the invention is to provide a garment hanger provided with a wire formed frame of improved construction for supporting the desired number of hose clips, the frame being provided with a swiveled hook permitting it to be suspended in different positions with respect to the plane of the hook thereby materially enhancing the usefulness of the device.

Still another object of the invention is to provide a hose hanger or the like having a supporting frame for a series of hose clips formed in two upper and lower parallel courses or bars, the clips being supported for turning motion on the lower bar and arranged so that the extent of rotation or angular movement thereof is limited by the upper bar.

Other objects of this invention will appear in the following description and appended claims, reference being had to the accompanying drawings forming a part of this specification wherein like reference characters designate corresponding parts in the several views.

Fig. 1 is a front elevation of a hanger constructed in accordance with the present invention.

Fig. 2 is an end elevation.

Fig. 3 is a perspective view of a hose clip.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, a wire formed hanger for hose or other

2

garments comprising a supporting frame upon which a series of spring wire clips are mounted. The frame is preferably formed from a single length of heavy gage wire bent intermediate its ends at 10 to provide a lower horizontal bar 11 upon which the clips are mounted. From the return bends 10 the wire is extended inwardly to provide sections 12 arranged end to end but spaced apart a suitable distance midway of the frame. These sections or portions 12 preferably extend parallel to the lower bar 11 and are suitably spaced vertically thereabove to lie in a common plane with the bar 11.

Interposed between the ends of the frame sections 12 is a connector or coupling element 13 comprising a metal piece coiled at opposite ends to provide tubular sockets 13a fitting over the ends of the sections 12 and rigidly secured thereto. The piece 13 has a vertical hole through which 15 extends the lower end of the shank 14a of a hook 14. The terminal end of the shank is headed or peened at 14b to prevent withdrawal and is upset at the upper side of connector piece 13 to provide lugs 14c. The portions 14b and 14c interlock the hook shank and connector piece and prevent the shank from sliding vertically in either direction relative to the frame. A swivel connection is thus provided permitting the hook to be rotated relative to the frame.

20 Mounted on the lower bar 11 are a series of wire formed spring clips 15 all formed in identical manner, four such clips being illustrated by way of example. Each clip is preferably formed from a single length of wire of smaller gage than the

25 wires of the frame. By placing the frame in a suitable jig the clips may be fabricated directly on the bar 11 by bending and shaping the wire through the use of mechanism provided for this purpose. Each clip comprises a pair of expandable and contractable gripping jaws or elements 16

30 and 17 which may be spread apart by means of a pair of diverging finger gripping pieces or elements 18 and 19.

35 As illustrated, one end of the wire of each clip is coiled at 20 tightly around the bar 11. Thence, the wire is extended downwardly and bent to provide the sides 16a and 16b as well as the bottom of one depending U-shaped gripping jaw or element 16 of the clip. From the side 16b the wire is coiled around the bar at 21, and thence 40 it is extended upwardly and bent to form the sides 18a and 18b as well as the outer end of a U-shaped finger gripping piece 18. From the side 18b the wire is coiled a number of times at 45 22 tightly around the bar 11, and thence it is extended upwardly and bent to provide the sides 19a and 19b as well as the outer end of the second

finger gripping piece 19. From the side 19b the wire is coiled once at 23 around the bar 11 and thence extended downwardly and bent to provide the sides 17a and 17b as well as the bottom of the second gripping jaw or element 17. From the side 17b the end of the wire is coiled at 24 around the bar. It will be noted that the end coils 20 and 24 of the wire snugly embrace the bar 11 and lie just outside the coils 21 and 23, and that the construction is such that no sharp projections occur which might snag the hose and cause damage thereto during use.

The formation of the coils of the clip is such that the outer ends of the jaws are at all times urged inwardly into gripping engagement by spring action. When in this position the finger gripping members 18 and 19 extend upwardly in diverging relation. Hence, in order to spread or expand the jaws it is merely necessary to grip the ends of the members 18 and 19 between the thumb and forefinger and press them together. When released the jaws will spring together and grip the hose or garment securely therebetween. The several coils 20-24 are preferably snug on the bar 11, the wire being tightly wound to form these coils in order to cause them to frictionally grip the bar and resist displacement longitudinally thereof. Thus, during normal use the clips will remain firmly in predetermined positions on the bar. However, they may be relatively adjusted by exerting sufficient pressure to slide them along the bar.

It will further be noted that the clips are free to turn or rotate to a limited extent on the bar 11, a desirable feature in the use of the device. This permissive turning of the clips is, however, limited so that the clips at all times will be positioned upright on the bar as shown in the drawings. The upper portions 12 of the frame provide stops to limit rotation of the clips on the bar 11. Since the finger pieces 18 and 19 straddle the portions 12 it will be readily seen that the clip can turn on the bar 11 in one or the other direction only a short distance until one finger piece or the other strikes the bar portion 12.

The present device is especially useful for hanging stockings to be dried. The top of each stocking may be gripped between the ends of the jaws of one of the clips and the stocking allowed to hang down to dry. The frame may be conveniently hung by the hook 14 from a support. By turning the hook into a plane at right angles to the plane of the members 11, 12 it will be seen that the hook may engage over the horizontal bar of any conventional towel or wall rack while permitting the frame to be disposed immediately beneath and parallel to the bar. Thus, an important advantage of the present hanger resides in the fact that the hook may be positioned at any desired angle with respect to the frame enabling the device to be suspended from any wall bracket, hook, rack or other object.

I claim:

1. A garment hanger comprising a supporting frame including a wire member, and one or more garment clips mounted on said member, each clip comprising a pair of cooperating garment gripping portions depending from said member and a pair of finger gripping portions extending upwardly from said member, said clip being formed from a single length of wire and having a plurality of spring coils at the juncture of said pairs of garment and finger gripping portions through which said member extends.

2. A garment hanger comprising a supporting

frame including a wire member, and one or more garment clips mounted on said member, each clip comprising a pair of cooperating garment gripping portions depending from said member and a pair of finger gripping portions extending upwardly from said member, one of said pairs being of less width than the other pair and said clip being formed from a single length of wire and having a spring coil at the juncture of said pairs through which said member extends.

3. A garment hanger comprising a supporting frame bar, a garment clip mounted on said bar and comprising a length of wire bent to provide a pair of finger gripping portions and a pair of garment gripping portions, one pair extending oppositely to the other pair, said wire also being coiled at the juncture of said pairs to provide a plurality of aligned convolutions through which said bar extends.

4. A garment hanger comprising a supporting frame bar, a garment clip mounted on said bar and comprising a length of wire bent to provide a pair of finger gripping portions and a pair of garment gripping portions, one pair extending oppositely to the other pair, the inner proximate ends of all of said portions being coiled around said bar and such coils extending in alignment.

5. A garment hanger comprising a supporting bar, a garment clip mounted on said bar and comprising a length of wire formed to provide a pair of generally U-shaped finger gripping portions and a pair of generally U-shaped garment gripping portions, one pair extending oppositely to the other pair, the inner proximate ends of all of said portions being coiled around said bar, and said wire also being formed into a number of coils lying between the inner ends of one of said portions and through which said bar extends.

6. A garment hanger comprising a supporting frame including a length of wire bent to provide a continuous lower member and an upper member parallel thereto, a clip connecting the adjacent ends of the wire centrally of the upper member, a hanger hook swiveled to said clip, and one or more garment clips mounted on said lower member, each clip comprising a length of wire formed to provide a pair of upwardly extending diverging finger gripping portions embracing the upper member and a pair of depending garment gripping portions, the inner ends of all of said portions being coiled around said lower member.

7. A garment hanger comprising a frame including a round bar and a garment gripping clip mounted thereon, said clip being formed from a length of wire bent to provide oppositely extending finger gripping and garment gripping portions and formed with a number of aligned coils at the juncture of said portions embracing said bar.
